BARREL CONVEYER

Adelbert J. Schenk, Cincinnati, Ohio, assignor to
 The Alvey-Ferguson Company, Cincinnati,
 Ohio, a corporation of Ohio

Application April 2, 1940, Serial No. 327,490

3 Claims. (Cl. 198—189)

This invention relates to improvements in endless conveyers, principally of the single chain type, particularly adaptable for the conveyance of barrels, or casks or kegs; the barrel being a double conoid having its greater diameter in its center, the center generally being referred to as the bulge or bilge, with a curved taper from the center to the extremities, and for metal barrels in addition a pair of spaced annular ribs, usually extending outwardly from the center or bilge, presenting an article which cannot appropriately be handled upon a chain conveyer having uniform flights.

The barrel when set on its side is easily rolled, but due to smaller diameters at its extremities, is easily thrown out of balance and will sway from side to side. As it is desirable to roll the barrels on their sides, at random, at any point onto the continuously traveling conveyer, they therefore are rolled onto the conveyer in a direction transverse to the line or direction of travel of the conveyer. As the barrel alights on the conveyer, it will be jarred, having a tendency to throw it axially out of the line with the conveyer so that one or both ends will ride or slide upon the guide or guard rails, usually disposed at opposite sides of the conveyer, or maneuvered about as the barrel is conveyed, imposing additional loads and wear upon the conveyer equipment and effecting injury to the barrel surfaces.

In existing conveyers, the barrels, for one type, are supported by and upon two parallel strands of chains, between which the barrel is interposed which multiplies the conveyer cost and has serious objections in its maintenance. A second type provides a single chain with uniformly spaced flights for the upper side of the chain, presenting a pair of upwardly extending horns at opposite sides of the chain upon which the barrel is intended to rest, so that two adjacent pairs of horns are adapted to afford vertical supports for the barrel at four points clear of the body portion of the chain with the center of gravity located between said four points, and relying upon a relative self-adjustment of a pair of points by the pivotal connection of the links of the chain about a vertical axis, to stabilize seating of the barrel on said four points. Owing to the peculiar contour of the barrel, and under the prevailing practice of rolling the barrel sidewise upon the traveling conveyer, it has been experienced that the four point support condition in practice, is seldom realized unless centered upon the four points initially, which it is difficult to perform by rolling the barrels upon the conveyer haphazardly and

in no timed relation to the moving flights. It is capable of landing upon two points, and under the alighting jar swings to one side or the other so that one end contacts and rides upon one of the side rails, from which position it cannot be self dislodged to become stabilized or centralized in line with the travel of the chain to bring it into a four point support position.

According to the present invention, the chain may be of any well known or conventional type, 10 the chain construction being optional, having each alternate link, designated as a main link, provided at its underside with a shoe formed with an extended width of base for slidingly supporting the chain and for the chain assembly at regularly spaced intervals when the chain is employed as a drag chain. The chain may be equipped with rollers, which, however, adds materially to the cost. The main links and as companion with each 15 shoe, for the upper side of the chain, alternately are provided with a crescent shaped or double point support, and a relatively flat or shallow shaped comparatively large face support or centering plate. The crescent or double pointed attachment for every other main link will grasp two points on the barrel circumference, while the approximately flat or shallow broad faced plate provides a third point contact, leaving the barrel free to roll or shift to the center line of the plate or chain if out of line therewith, and thereupon 20 stabilized centrally upon the chain.

It is an object of the invention to provide a chain conveyer for conveying barrels, each in a stabilized position to lie axially longitudinally with the center line of the conveyer, and adapting the barrels to be loaded onto the conveyer at any point by rolling the same sidewise thereon and effecting a self-centralizing and stabilization with the center line of the chain.

Another object of the invention is to provide a chain conveyer for barrels and the like articles, adapting the barrel to be supported free from the chain upon three points of contact, two in spaced alignment crosswise of the chain, and for the third upon a shallow faced support centrally of the chain, the latter to permit the barrel readily to shift by gravity from an off-center to a central and stabilizing position.

Another object of the invention is to provide a 50 chain conveyer for barrels, employing a conventional chain adapting flight or barrel supporting fixtures to be removably applied to the links thereof, and at selected intervals, and alternately as a lateral two point support and a centralizing plate support at relatively different elevations for

establishing and maintaining a tri-support for the barrel upon the chain longitudinally axially in line with the center line of the chain.

Another object of the invention is to provide a chain conveyer primarily for conveying barrels of simple and durable construction, upon which the barrels can be loaded by rolling thereon at random at any point therealong, and centrally sustained thereupon, free from any drag upon guard or side rails which form a channel in which the active run or runs of the chain travel.

Further objects and advantages of the invention will be more fully apparent from a description of the accompanying drawing, in which:

Figure 1 is a top plan view of a section of the 15 conveyer run.

Figure 2 is a side elevation of a portion of the conveyer run with the channel beam guideway shown in section.

Figure 3 is a cross section taken on line 3—3, 20 Figure 2.

Figure 4 is an enlarged sectional view taken on line 4—4, Figure 2.

Figure 5 is an enlarged sectional view similar to Figure 4, taken on line 5—5, Figure 2.

In the drawing, only a section of a barrel supporting run of the conveyer is illustrated, deemed as sufficient to exemplify the present invention, and of a construction for use when the conveyer is set into a floor. The forward and return runs of the conveyer preferably are relatively disposed to move about sprockets, rotating on a vertical axis, so that both runs are in an upward active position. They, however, may be superposed in a vertical plane, in which instance the return 30 run, being in an inverted position, is idle.

The course or relation of the runs may follow any conventional practice most suitable for a given installation, and the conveyer likewise may be sustained upon a framework extending above a floor level.

The conveyer chain illustrated is of conventional type constituting, alternately, an integral link 1, designated as a main link, with each of its opposite ends respectively pivotally connected to a pair of connecting links 2, 2, disposed relatively at opposite sides or outward of the main link. The main link 1 is in the form of an apertured bar, having its opposite ends 3, 3, of greater width than the opposite longitudinal side portions, to each of which a pair of connecting links 2, 2, are pivotally connected by a pin 4. The body portion of the main link has a longitudinal aperture therethrough, into which the chain and barrel supporting attachments are socketed for their connection to the main link. The chain links in the present instance are disposed so that they are connected for pivotal movement about a vertical axis as offering adequate chain flexibility when the strands or runs or both are relatively horizontal. A universal connection may, however, be interposed should the course of the runs so require.

The chain structure forming no part of the present invention, it is recognized that it may be composed of various specific forms of links and give equal service to the form illustrated, which, however, is of standard type of which its parts for making repairs are readily available, and its selection primarily has been for that reason.

Each main link at its under side carries a shoe 5 providing a flat faced base of extended width, affording a substantially sliding support for the chain. A shank 6 extends laterally or vertically from the upper side of the base, and its upper

end longitudinally is formed with a tenon 7 for making a mortise or socket connection with the aperture of the main link and bearing against the opposite lower edges of the link.

5 The base surface of the shoe slides upon a wearing strip or rail 8 mounted within a structural iron channel beam or guideway 9 suitably anchored to the base of the trough 10 formed in the floor when the conveyer is installed beneath the floor level; or when the conveyer is installed above the floor, the channel 9 is usually fixed to the framework for the conveyer. The upper opposite edges of the trough are lined with structural angle bars 11, 11, furnishing a curbing for the trough, and also serve as side guards or rails for the conveyer. Guards correspondingly are provided when the conveyer is set directly on the floor, or when raised above the floor following the usual practice for conveyers of this class.

10 The chain assembly shown in preferably contemplated for conveying the standard one-half barrel size of barrels used for packaging beer with the main links having a center spacing of approximately eight inches. Each main link in such instance at its upper side carries a barrel supporting attachment or fixture in companion connection with a shoe on the lower side thereof.

Figure 4 is an enlarged sectional view taken on line 4—4, Figure 2.

15 Two differently shaped types of barrel supporting attachments or fixtures 12, 13, are employed; one of which, as attachment 12, for each alternate link, is of crescent or arc shape to constitute a pair of uniform upwardly diverging horns or claws 14, 14, extending laterally of the chain with their extremities providing two laterally aligned points above the chain for contact and grasp on the barrel circumference. The hollow or arc in the top side of the attachment is of a radius as indicated in Figure 5, smaller than the smallest diameter at the opposite ends of the barrel, so that the barrel cannot seat or rest upon the hollow or arc. The fixture at its lower side similarly to the shoes is centrally provided longitudinally of the chain with a lateral shank extension, having a tenon formed on its outer end for making a mortise or socket connection with the aperture of the main link, and opposingly to the shoe and rigidly secured with the shoe to the link by a pair of bolts or rivets engaged therethrough and traversing the aperture in the link for claspingly binding the shoe and barrel supporting fixture to the link.

20 A second barrel supporting attachment or fixture 13 for each alternate main link or intermediate of a pair of fixtures 12 comprises a relatively flat or shallow longitudinally dished or concave plate of appropriate length, so as to give the same an extended barrel receiving area and guidingly direct to a centralized position with the chain when the barrel is deposited upon the conveyer.

25 The concavity in the upper or face side of the plate, as illustrated in Figure 4, is of a radius larger than that of the largest diameter of the barrel, as at the bilge portion thereof, so that its extremities are devoid of offering any supporting points for the barrel. The radius on the centering plate is merely sufficient to permit a slight gravity barrel roll or shift to allow it to self center with the center line of the chain, and thereby provide a central third point of contact as intermediate of the two points of the adjacent crescent or horn-shaped fixture which support the barrel on points at an equal distance on either side of the chain while the third point of con-

tact on the plate fixture will be directly over the chain.

The plate fixture 13 on its outer side is provided with a laterally extended shank similar to the fixtures 12 and shoes for a connection to a chain link and a companion with the shoe.

The central plane of the centering plate fixture 13 is preferably at a slightly lower elevation than the reach of the point extremities of the crescent shaped fixture to insure a two-point barrel sustaining contact with an extreme end of the barrel and avoid the plate fixture from becoming a sole support should the bilge of the barrel in loading upon the conveyer alight centrally on the plate fixture on account of the barrel having a curved taper toward its extremities or curved longitudinally. The smooth surface of the plate fixture will permit longitudinal movement of the barrel due to counter force imposed by the chain which is moving transverse to the alighting motion of the barrel upon a conveyer, so that there is no tendency to dislodge it from a two point contact with either a fore or aft crescent attachment 12, whichever one it engages, and as it is free to rock or shift laterally upon the plate fixture, it will immediately establish itself to a central stabilizing position upon the plate fixture.

In rolling the barrel onto the conveyer at any point, the shape of the lower or shallow plate attachment 13 allows the barrel to shift readily, and it finally becomes stabilized on three points after having aligned itself with the center line of the conveyer. This is because any three points of contact will stabilize it, and until the barrel shifts into position and finally contacts the high attachment, it does not stabilize. If the barrel is rolled on so that it hits the high attachment, then one end or the other of the barrel drops to the lower or shallow center attachment. When either end drops to the shallow attachment, it normally will hit the attachment in the center with just enough force to center it if it is not already centered. It is a known fact that any three points of contact or rest will stabilize an object. Therefore, enough play will be provided between the attachment and the barrels so that the barrels have a tendency to shift onto the center line of the chain before stabilizing on three points. On previous designs, attempts were made to keep the barrel from doing the shifting, with the result that whatever position the barrel had when it was rolled onto the conveyer, that position was maintained throughout its travel.

The relative alternate differential flights allow the barrels to shift as the supporting chain links round a curve, which moves the longitudinal axis of the barrel slightly out of line with the links,

and to self-correct its position to centralize with the chain as soon as the travel is again in a straightway course. This relative action was not possible with the uniform type of flights heretofore employed.

Having described my invention, I claim:

1. A conveyer chain for conveying barrels and the like, comprising: main links and connecting links pivotally united, a shoe respectively fixed to each main link for the under side of the chain to provide uniformly spaced sliding supports therefor, a crescent shaped flight respectively fixed to each alternate main link for the upper side of the chain, each to provide a pair of spaced points aligned laterally of the chain for partially supporting a barrel, and a second flight respectively fixed to each alternate main link and intermediate of a pair of crescent shaped flights extending transversely of the chain and having its upper side formed to provide a bearing surface for its full width adapted with an adjacent crescent shaped flight to afford a tri-support for a barrel, the bearing surface of said second flight being slightly concave laterally adapting the barrel to self-centralize itself with the center line of the chain.

2. A conveyer chain for conveying barrels and the like, having crescent shaped flights respectively fixed at uniform spacing apart to the upper side of the chain, each to provide a pair of spaced barrel supports aligned laterally of the chain for the partial support of a barrel, and second flights respectively fixed to the upper side of the chain at uniform spacing apart and each intermediate of a pair of crescent shaped flights and extending transversely of the chain and having its upper side formed to provide a bearing surface for its full width to adapt it with an adjacent crescent shaped flight to afford a tri-support for a barrel, the second flight adapting the barrel to self-centralize itself with the center line of the chain.

3. A conveyer chain for barrels and the like, having relative differential barrel supports in spaced alternate arrangement extended above the chain, one having a pair of spaced claws for supporting the barrel at relative opposite sides of the chain, and a second barrel bearing surface extending transversely of and beyond the opposite sides of the chain and at a lower elevation than the supporting elevation of an adjacent pair of claws, and adapted therewith to afford a tri-support for a barrel, the bearing surface of the second providing a self-centralization of the barrel with the chain.

ADELBERT J. SCHENK.
